PASTE DISPENSER

William H. Coates, Montreal, Quebec, Canada

Application March 22, 1937, Serial No. 132,381

2 Claims. (Cl. 221—60)

This invention relates to paste dispensers especially adapted for dispensing dental, shaving or facial creams without soiling the hands of the user and has for the primary object the provision of an efficient, durable and inexpensive device of this character which will support and protect from foreign matter a collapsible tube or container and its contents and has a simple manually actuated means to compress the tube for expelling the contents thereof in amounts as desired.

With these and other objects in view, this invention consists in certain novel features of construction, combination and arrangement of parts to be hereinafter more fully described and claimed.

For a complete understanding of my invention, reference is to be had to the following description and accompanying drawing, in which

20 Figure 1 is a front elevation partly in section illustrating a dispenser constructed in accordance with my invention.

Figure 2 is a side elevation illustrating the device.

25 Figure 3 is a sectional view taken on the line 3—3 of Figure 1.

Figure 4 is a sectional view taken on the line 4—4 of Figure 1.

Figure 5 is an end view illustrating a closure 30 valve employed in the construction of this device.

Figure 6 is a sectional view taken on the line 6—6 of Figure 5.

Figure 7 is a detail vertical sectional view illustrating a modified form of valve.

Referring in detail to the drawing, the numeral 1 indicates a casing having secured to its rear wall one of the sections of a wall clamp 2 while the other section of the clamp is fastened to a wall or the like of a room so that the casing will be supported in a vertical position. The bottom of the casing is in the form of a removable closure 3 held on the casing by spring catches 4 engaging in openings provided 40 in walls of the casing. The bottom of the casing has an opening to permit a discharge neck 5 of a collapsible tube 6 to extend therethrough when said tube is arranged in the casing in an inverted position.

50 A side wall of the casing has formed therein a slot 7 which opens outwardly through the lower end of the casing and is normally closed at said lower end of the casing by the closure 3.

55 A frame 8 is slidably mounted in the casing 1

and includes substantially rectangular-shaped end plates 9 connected by rods 10 and also having journaled in openings thereof a shaft 11, one end of which extends through the slot 7. The extended end of the shaft has a finger piece 12 secured thereto. The shape of the plates 9 of the frame 8 is such that the frame will be free to slide in the casing but will be held against a rotary motion within the casing. Journaled on the rods 10 are sleeves 13. The sleeves have 10 mounted thereon cushion rollers 14. The shaft 11 is positioned above and between the rollers and has a slot 15 to receive the non-open end of the tube 6. In other words, the non-open end of the tube is passed through the slot 15 and bent 15 into engagement with the shaft 11 after being passed between the rollers 14 so that upon rotation of the shaft 11 the container will be wound on the shaft in a substantially flat condition, the rollers acting to compress the container or tube 20 and consequently expel therefrom the contents. By controlling the rotation of the shaft 11 the amount of the contents expelled from the container by the neck 5 may be controlled.

A valve housing 16 is threaded on the neck 5 of 25 the container after the neck has been passed through the closure 3 of the casing. A seat 17 is formed in the valve housing and is engaged by a shoulder 18 formed on an elastic sleeve 19 which extends out of the valve housing. A ball 20 is located in the sleeve 19 and the diameter thereof is 30 slightly larger than the interior diameter of the sleeve 19 so that said sleeve tightly fits the ball and thereby forms a valve closure for the neck 5 of the tube 6. The ball 20 is mounted on a 35 rod 21 and the latter is secured to the flange 18 of the sleeve 19 by a cross rod 22. When pressure is applied to the contents of the tube, the contents expands the sleeve 19 and passes about 40 the ball 20 to escape from said sleeve and as soon as the pressure is released on the tube the sleeve 19 contracts against the ball so as to close the contents of the container against atmospheric conditions and foreign matter.

45 Instead of using the type of valve as shown in Figure 6, a type as shown in Figure 7 may be employed and consists of a valve housing 23 having a bore 24 extending therethrough and a portion of which is screw threaded to thread onto 50 the neck 5. A valve element 25 of the plug type is journaled in the valve housing 23 and has a port 26 which may be positioned into and out of communication with the bore 24. A handle 27 is secured to the valve element 25 whereby the 55

valve element may be rotated to open or close the valve housing 23.

When either of the valves, as shown in Figures 6 and 7 is applied to the neck of the tube 6 it will

5 prevent said tube from becoming disarranged in the casing 1 and provides a simple means which will permit the easy removal and replacement of a tube in the casing when desired.

What is claimed is:

- 10 1. A paste dispenser comprising a vertically arranged casing having a removable bottom provided with an opening to receive a neck of a collapsible tube with the latter arranged in an inverted position within said casing, a frame 15 slideable in said casing, said casing having a slot, spaced cushion rollers carried by said frame and receiving therebetween the tube, a shaft journaled in said frame and extending through the slot and having a slot to receive one end of the tube, a finger piece secured to said shaft whereby the tube may be wound on the shaft to bring about expelling of the contents of the tube by the rollers, a valve housing threaded onto the neck and against the cover and having a seat, an elastic sleeve extending out of said valve housing and having a flange to engage the seat, and a
- 15
- 20
- 25

ball supported in the sleeve and of a diameter slightly greater than the interior diameter of the sleeve.

2. A paste dispenser comprising a vertically arranged casing having a removable bottom provided with an opening to receive a neck of a collapsible tube with the latter arranged in an inverted position within said casing, a frame 5 slideable in said casing, said casing having a slot, spaced cushion rollers carried by said frame and receiving therebetween the tube, a shaft journaled in said frame and extending through the slot and having a slot to receive one end of the tube, a finger piece secured to said shaft whereby the tube may be wound on the shaft to bring 15 about expelling of the contents of the tube by the rollers, a valve housing threaded onto the neck and against the cover and having a seat, an elastic sleeve extending out of said valve housing and having a flange to engage the seat, 20 a valve housing threaded on the neck against the cover and having a bore therethrough, a valve element for opening and closing the bore and journaled in said valve housing, and a finger piece secured to said valve element.
